UNITED STATES PATENT OFFICE.

JACOB E. GRAMLICH, OF SYRACUSE, NEW YORK, ASSIGNOR TO CHASE MOTOR TRUCK CO., OF SYRACUSE, NEW YORK, A CORPORATION OF NEW YORK.

CENTRIFUGAL FAN.

1,169,476.

Specification of Letters Patent. Patented Jan. 25, 1916.

Application filed March 14, 1914. Serial No. 624,691.

To all whom it may concern:

Be it known that I, JACOB E. GRAMLICH, a citizen of the United States, and a resident of Syracuse, in the county of Onondaga and 5 State of New York, have invented a certain new and useful Centrifugal Fan, of which the following is a specification.

This invention has for its object the production of a centrifugal fan particularly applicable for use as a fly wheel for air cooled engines for drawing air through the hood and boot surrounding the engine; and the invention consists of the novel features of construction hereinafter set forth and 15 claimed.

In describing this invention, reference is had to the accompanying drawings, in which like characters designate corresponding parts in all the views.

20 Figure 1 is a face view, partly broken away, of this fan. Fig. 2 is a cross-sectional view thereof, partly in elevation.

This fan comprises, generally, a body including front and rear heads 1, 2 and vanes 25 3 between the heads, the front head 1 at the receiving end of the fan having an enlarged inlet opening 4 so that the front head is practically a flat ring at the margin of the fan, and the rear head 2 being solid and 30 closing the rear end of the fan and being integral with the hub 5 of the fan. The central portion or zone of the rear head 2 inclines forwardly as it approaches the hub, toward the front or receiving side of the 35 fan and forms a cone 6.

The vanes 3 are formed integral with the heads 1, 2 and extend inwardly terminating near the center or hub of the fan and incline in a lengthwise direction so that the 40 portions thereof exposed through the receiving opening 4 have a lead as they approach their inner ends; in other words, the vanes extend in tangential directions relatively to the axis of the fan, that is, they incline inwardly in the direction of rotation of the fan, the fan rotating in the direction of the arrow, Fig. 1. The portions of the vanes behind the front head 1 extend in substantially radial directions.

45 The front edges of the portions of the vanes exposed through the opening 4 are cut inwardly along concave lines as 7 extending from the inner edge of the front head 1 and extending toward the inner ends of the vanes and terminating near the front

head 2 or cone 6 thereof and near the hub 5. The vanes are thicker at their outer ends, that is, their portions lying behind the front head 1 are thickened and formed with concave faces 8 on the advance sides of the 63 vanes which form continuations of the front faces of the tangential or inclined portions of the vanes. The rear sides of the thickened ends of the vanes are convex, as at 9, and form continuations of the rear faces of the inclined portions of the vanes, but the curvature thereof is less than the curvature of the advance sides of the vanes. The thickened ends of the vanes increase gradually in thickness as they approach the rear 70 head 2, the increased thickness lying on the rear sides of the vanes. This increased thickness of the vanes is due to tapering the vanes of the pattern so that the pattern can be readily withdrawn out of the molding 75 sand. Owing to this arrangement of the vanes and the shape of the outer ends of the vanes, a particularly powerful and efficient fan is produced, that is, the vanes, owing to their incline, take the air and move 80 it outwardly to the radially extending concave faces which cause the air to be hurled away from the fan.

This fan is particularly designed to be used as a fly wheel for internal combustion 85 engines, and in operation owing to the formation of the vanes and the cone, moves the air outwardly with accelerated motion through the gradually widening spaces between the vanes to the concave faces at the 90 ends of the vanes which hurl the air away from the fan.

What I claim is:—

1. A centrifugal fan comprising a body including front and rear heads, the front head at the receiving end of the fan having an opening, the rear head closing the rear end of the fan, and vanes between the heads of the fan, the portions of the vanes exposed through the receiving opening inclining 100 and having a lead in a forward direction as they approach the axis of the fan, and the portions of the vanes behind the front head extending in radial directions, substantially as and for the purpose set forth. 105

2. A centrifugal fan comprising a body including front and rear heads, the front head at the receiving end of the fan having an opening, and the rear head closing the rear side of the fan, and vanes between the 110

- heads of the fan, the vanes extending in a tangential direction relatively to the axis of the fan and terminating at their inner ends near the center of the fan, the portions of 5 the vanes exposed through the receiving opening having their inner portions cut away along lines extending from the inner margin of the front head at the receiving end of the fan and extending toward the 10 rear head of the fan and inwardly to the inner ends of the vanes, the outer end portions of the vanes lying directly behind the front head, extending in radial directions, substantially as and for the purpose de- 15 scribed.
3. A centrifugal fan comprising a body including front and rear heads, the front head at the receiving end of the fan having an opening, and the rear head closing the 20 rear end of the fan, and vanes between the heads of the fan, the vanes extending in tan- 25 gential directions relatively to the axis of the fan and terminating at their ends near the center of the fan, the vanes being thick- 30 ened at their outer ends, and the front faces of the thickened outer ends being concave the rear sides of the vanes at their outer ends being convex, substantially as and for the purpose described.
- 35 4. A centrifugal fan comprising a body including front and rear heads, the front head at the receiving end of the fan having an opening, the rear head closing the rear end of the fan, and vanes between the heads 40 of the fan, the portions of the vanes ex- 45 posed through the receiving opening inclining and having a lead in a forward direction as they approach the axis of the fan, and the portions of the vanes between the front end being thickened and extending in radial di- 50 rections, substantially as and for the purpose specified.
5. A centrifugal fan comprising a body including front and rear heads, the front head at the receiving end of the fan having an opening, the rear head closing the rear end of the fan, and vanes between the heads of the fan, the portions of the vanes exposed through the receiving opening inclining and 55 having a lead in a forward direction as they approach the axis of the fan, and the portions of the vanes behind the front head be- 60 ing thickened and extending in radial di- 65 rections, and the front faces of the thickened 70 portions being concave and forming continuations of the front faces of the inclined leading portions of the vanes, substantially as and for the purpose set forth.
6. A centrifugal fan comprising a body including front and rear heads, the front head at the receiving end of the fan having an opening, the rear head closing the rear end of the fan, and vanes between the heads of the fan, the portions of the vanes exposed through the receiving opening inclining and 75 having a lead in a forward direction as they approach the axis of the fan, and the portions of the vanes behind the front head be- 80 ing thickened and extending in radial di- 85 rections, and the front faces of the thickened portions being concave and forming continuations of the front faces of the inclined leading portions of the vanes, and their rear faces being convex, substantially as and for the purpose described. 75
7. A centrifugal fan comprising a body including front and rear heads, the front head at the receiving end of the fan having an opening, the rear head closing the rear end of the fan, and the central portion or 80 zone thereof inclining forwardly as it ap- 85 proaches the axis of the fan forming a cone, and vanes between the heads, the portions of the vanes exposed through the receiving opening and lying on the cone having a lead in a forward direction as they approach the axis of the fan, said portions of the vanes exposed through the receiving opening hav- 90 ing their forward edges located in lines ex- 95 tending from the inner edge of the front head of the fan and terminating near the inner ends of the vanes near the rear head, and the outer ends of the vanes being thick- 95 ened, and the thickened ends being formed with concave front faces and convex rear faces forming continuations of the front and rear faces of the vanes, substantially as and for the purpose specified.

In testimony whereof, I have hereunto signed my name in the presence of two at- 100 testing witnesses, at Syracuse, in the county of Onondaga, in the State of New York, this 9th day of Mar., 1914.

JACOB E. GRAMLICH.

Witnesses:

K. F. RANGER,
C. A. DUKIE.

It is hereby certified that in Letters Patent No. 1,169,476, granted January 25, 1916, upon the application of Jacob E. Gramlich, of Syracuse, New York, for an improvement in "Centrifugal Fans," an error appears in the printed specification requiring correction as follows: Page 2, line 39, claim 4, for the word "between" read *behind*; and that the said Letters Patent should be read with this correction therein that the same may conform to the record of the case in the Patent Office.

Signed and sealed this 24th day of April, A. D., 1917.

[SEAL.]

F. W. H. CLAY,
Acting Commissioner of Patents.
